CLAIM

The ornamental design for a dental pick device, as shown and described.

DESCRIPTION

FIG. 1 is a left side perspective view of a dental pick device showing our new design;

FIG. 2 is a left side elevation thereof;

FIG. 3 is a right side elevation thereof;

FIG. 4 is a top plan thereof;

FIG. 5 is a bottom plan thereof;

FIG. 6 is a front elevation thereof; and,

FIG. 7 is a rear elevation view.

The broken lines in the drawings are for illustrative purposes only and form no part of the claimed design.
